CLAIM

The ornamental design for a sound reduction headset, as shown and described.

DESCRIPTION

FIG. 1 is a front perspective view of a sound reduction headset showing our new design;

FIG. 2 is a front elevational view, the rear elevational view being the mirror image thereof;

FIG. 3 is a left side elevational view, the right side elevational view being the mirror image thereof;

FIG. 4 is a top plan view thereof; and

FIG. 5 is a bottom plan view thereof.

The broken lines in FIG. 1 represent the shape and positioning of ear cups and form no part of the present invention.
